ELECTRICAL SWITCH.

1,345,899.

Specification of Letters Patent.

Patented July 6, 1920.

Application filed June 12, 1918. Serial No. 239,675.

To all whom it may concern:

Be it known that we, HENRY R. STEVENS and ROBERT L. ROCKWELL, citizens of the United States, residing at Seattle, in the county of King and State of Washington, have invented a new and useful Improvement in Electrical Switches, of the class commonly termed "limit-switches," of which the following is a specification.

10 This invention relates to improvements in electrical switches of the class commonly termed "limit switches", and is especially adapted for use in connection with the electrical control system for railway track sections, illustrated and described in our co-pending application of even date herewith.

15 The object of this improvement is to provide a switch of this nature that is simple in its form of construction and reliable in 20 its operation.

A further object is to provide a limit switch that will make a contact between one set of switch terminals at the same time that it breaks the contact between another set of 25 switch terminals.

30 A still further object is to provide a limit switch of this class that will make a momentary electrical contact when it is thrown in one direction but will not make a similar momentary contact when thrown in the opposite direction.

35 In the accompanying drawings, Figure 1 is a plan view of a limit switch constructed in accordance with this invention, and Fig. 2 is a view in side elevation of the device shown in Fig. 1.

40 Referring to the drawings, throughout which like reference numerals indicate like parts, the numeral 5 indicates a base or support for the switch mechanism.

45 Mounted on the base 5 adjacent one side thereof are a plurality of U-shaped terminals 6 that are adapted for the reception of switch blades 7, and mounted in a similar manner adjacent the opposite side of the base 5 are a plurality of similar terminals 8 adapted for the reception of switch blades 10. The switch blades 7 may be integral with the switch blades 10 and disposed at an angle thereto so that when the switch blades 10 are in contact with the terminals 8, as shown in Fig. 2, the switch blades 7

will be out of contact with the terminals 6, the switch blades 7 and 10 being medially pivoted in brackets 11.

55 The outer ends of the switch blades 7 are preferably all connected together by a bar of insulating material 12 and outer ends of the switch blades 10 are connected in the same manner by a similar bar of insulating 60 material 13 so that the blades will all move simultaneously.

65 The devices for making and breaking contacts between the switch blades 7 and the terminal 6 and the switch blades 10 and the terminal 8 comprise a frame 14, the lower end of which is pivotally mounted on a bolt 15 so that it may be swung from the position shown by full lines to the position shown by dotted lines in Fig. 2.

70 Within the upper portion of the frame 14 is provided a race or run-way 16 within which is disposed a relatively heavy cylindrical member 17 that is adapted to run from one end of the race 16 to the other 75 as the frame 14 passes the vertical position. The cylindrical member 17 thus serves to complete the throwing of the switch after it has been partly thrown by other means. The upper portion of the frame 14 is provided near opposite ends with pairs of spaced lugs 18 and 20 respectively between which a longitudinally movable bolt 21 is disposed, the bolt 21 having a cross pin 22 that successively engages with the lugs 18 85 or 20 as the bolt is moved endwise to lift the frame 14 into a vertical position from which it may be thrown downwardly by the weight of the cylindrical member 17 into the position shown by full lines or the position shown by dotted lines in Fig. 2.

80 The frame 14 is provided on each side with lugs 23 that engage with the insulated bars 12 and 13 to throw the switch as the frame 14 is thrown from one position to the 90 other.

95 It is apparent from the drawings that the switch blades 7 or 10 will not be disengaged from the terminals 6 or 8 with which they are in contact until after the frame 14 has 100 been moved into a substantially vertical position, and that when the switch is thrown it will be moved by the weight of the cylindrical member 17 as it rolls from one end

of the race 16 to the other, thus insuring that one set of contacts will be quickly broken and the other set of contacts quickly and completely closed.

- 5 In practice the bolt 21 may be any bolt that is actuated by a motor in the circuit in which the limit switch is interposed, the arrangement being such that at the end of a predetermined number of revolutions of the 10 motor the bolt will be moved a sufficient distance to cause the cylindrical member to be overbalanced and roll from one end to the other of the race 16, thereby breaking connections with one set of contacts, and making 15 connections with another set of contacts.

For the purpose of making a momentary electrical contact as the frame 14 is thrown in one direction and avoiding the making of 20 such momentary contact as the frame 14 is thrown in the opposite direction, a ratchet wheel 25 is provided. Such wheel in the construction herein shown has four symmetrically arranged peripheral notches 26 25 that are each insulated from the remainder of the wheel.

Disposed between the insulated notches 26 on the periphery of the wheel are contact members 27 that may be connected with 30 conductors 28 extending toward the center of the wheel.

The notches 26 are adapted for the reception of the end of a contact spring 29 that is secured to the frame 14 so that when the 35 frame 14 is moved from the position shown in full lines to the position shown in dotted lines in Fig. 2 the ratchet wheel will be moved therewith through an angle of substantially ninety degrees and no contact between the segments 27 and the spring 29 40 will be made, but when the frame 14 is moved from the position shown by dotted lines to the position shown by full lines in Fig. 2 the spring 29 will ride over the peripheral surface of the wheel and will make a momentary contact with one of the segments 45 27 before it drops into the insulated notch next in rear of the one it occupied.

The conductors 28 may all be connected at 50 the center of the ratchet wheel with a common circuit wire (not shown) and the spring 29 may be connected with another circuit wire (not shown) so that when the spring 29 makes contact with one of the segments 55 27 the circuit will be closed.

The ratchet wheel 25 is mounted on the bolt 15 and is provided on one side with a fixedly secured ratchet member 31 that is yieldingly held against a corresponding 60 ratchet member 32 which is fixed on the frame 5 by a spring 33 so that the ratchet wheel cannot be rotated in a contra-clockwise direction when the frame 14 is moved from right to left as viewed in Fig. 2.

65 By the arrangement of parts just de-

scribed it will be seen that the ratchet wheel will be advanced substantially one-fourth of one complete revolution every time the frame 14 is thrown from left to right as viewed in Fig. 2 and that the ratchet wheel 70 will remain stationary as the frame 14 is thrown from right to left.

It is obvious that changes in the precise form of construction of the various parts of this limit switch may be resorted to within 75 the scope of the appended claims.

What we claim, and desire to protect by Letters Patent, is:—

1. A switch of the class described comprising a base, a plurality of switch blades 80 each consisting of two straight rigidly connected sections formed at an angle to each other and pivotally mounted on said base, bars of insulating material connecting the outer ends of said switch blades, U-shaped 85 terminals mounted on said base for the reception of the ends of said switch blades, a pivotally mounted frame adapted to swing from one side to the other of a vertical plane passing through its pivot point to engage 90 with and throw said switch, a race formed in the top of said frame, a heavy roller in said race and adapted to roll from one end to the other of said race as said frame is oscillated from side to side, and means for moving 95 said frame.

2. A switch of the class described comprising a base, a plurality of switch blades each consisting of two straight rigidly connected sections formed at an angle to each 100 other and pivotally mounted on said base, bars of insulating material connecting the outer ends of said switch blades, U-shaped terminals mounted on said base for the reception of the ends of said switch blades, a 105 pivotally mounted frame adapted to swing from one side to the other of a vertical plane passing through its pivot point to engage with and throw said switch, a race formed in the top of said frame, a heavy roller in said 110 race and adapted to roll from one end to the other of said race as said frame is oscillated from side to side, means for moving said frame, a ratchet wheel pivoted on said base, contact members on the periphery of said 115 ratchet wheels and means connected with said frame and adapted to make a momentary contact with said contact members only when said frame is oscillated in one direction.

3. A switch of the class described comprising a base, a plurality of switch blades each consisting of two straight rigidly connected sections formed at an angle to each other and pivotally mounted on said base, bars of insulating material connecting the 125 outer ends of said switch blades, two sets of terminals mounted on said base on opposite sides of said switch blade pivots and adapted to make contact with the ends of said blades, a frame mounted on a pivot on 130

said base and adapted to swing from one side to the other of a vertical plane, a race provided in the top portion of said frame said race being arranged at substantially 5 right angles to a medial plane bisecting said frame, a weight disposed to roll in said race to effect a quick throw of said frame after it passes a medial point, lugs projecting upwardly from opposite ends of said frame, a 10 longitudinally movable bolt disposed to lie between said lugs and means on said bolt for engaging with said lugs to move said frame.

4. A switch of the class described comprising a base, two sets of U-shaped terminals mounted thereon in spaced apart relation, switch blades pivoted between said terminals and adapted to make contact therewith, said switch blades each being formed of two integral straight sections that are 15 bent at an angle to each other so that only one end at a time of said switch blades can make contact with said terminals, a pivotally mounted frame, adapted to oscillate from a position on one side to a position on the 20 other side of a vertical line that passes through the axis of the pivot about which such frame turns, said frame being adapted to engage with and move the said switch blades when it is oscillated to break contact 25 with one set of terminals and make contact with another set of terminals, a race in the upper portion of said frame, a cylindrical weight adapted to roll from one end to the other of said race when said frame is moved 30 from one side to the other of a vertical position, means for moving said frame, a ratchet wheel pivotally mounted on said base, means for preventing said ratchet wheel from turning in one direction, insulated portions in 35 the notches of said ratchet wheel, electrical contact members on the periphery of said wheel between said insulated portions and a spring pawl connected with said frame and adapted to engage within said notches 40 whereby when said frame is oscillated in one direction said spring pawl will move said ratchet wheel without making electrical contact therewith and when said frame is moved in an opposite direction said spring 45 pawl will slide over the periphery of said 50

ratchet wheel and make momentary contact with said contact members.

5. A switch of the class described, comprising an oscillating frame provided with a race in its upper portion, a weight adapted to run from one end to the other of said race, a switch adapted to be operated by the oscillation of said frame, a pivotally mounted ratchet wheel, means for preventing said ratchet wheel from turning in one direction, 55 insulated portions in the notches of said ratchet wheel, electrical contact members on the periphery of said ratchet wheel between said insulated portions, and a spring pawl connected with said oscillating frame and 60 adapted to engage within said notches whereby when said frame is oscillated in one direction said spring pawl will rotate said ratchet wheel without making electrical contact with said contact members and when 65 said frame is oscillated in an opposite direction said spring pawl will slide over the periphery of said ratchet wheel and make a momentary electrical contact with said contact members. 70

6. A limit switch comprising a base, an oscillating frame pivotally mounted on said base, a rotatably mounted ratchet wheel, said ratchet wheel having insulated sections in the notches thereof, and contact conducting sections in the periphery of said ratchet wheel between each of said insulated sections, means for preventing rotation of said ratchet wheel in one direction and a spring pawl carried by said oscillating frame and 75 engaging within the insulated notches in said ratchet wheel said spring pawl being adapted to make momentary contact with said conducting sections successively when said frame is oscillated in one direction and 80 being adapted to rotate said ratchet wheel 85 when said frame is oscillated in the opposite direction. 90
